UNITED STATES PATENT OFFICE.

OSCAR W. RICHARDSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-CARRIER MAGAZINE.

Application filed November 22, 1922. Serial No. 602,625.

To all whom it may concern:

Be it known that I, OSCAR W. RICHARDSON, a citizen of the United States, residing at Worcester, in the county of Worcester, 5 and State of Massachusetts, have invented a new and useful Weft-Carrier Magazine, of which the following is a specification.

This invention relates to a weft carrier magazine and particularly to improved devices for holding the weft carriers in the magazine from relative angular movement. In looms using a plurality of kinds or colors of weft, certain weft carriers may be used very infrequently and may thus remain in 15 the magazine for long periods of time. The vibration of the loom during a considerable period frequently causes relative angular movement of the weft carriers which entangles the weft ends and causes frequent 20 breakage of weft upon transfer.

It is the general object of my invention to provide an improved and simplified construction by which such angular movement of the weft carriers and consequent entanglement of the weft ends may be prevented. To this end, I provide means for yieldingly 25 gripping the weft carriers at the sides of the butts, together with means for releasing the pressure on the weft carriers upon indication of transfer.

Further details of my invention will be hereinafter described and more particularly set forth in the appended claims.

A preferred form of my invention is 35 shown in the drawings in which—

Fig. 1 is a partial side elevation of a weft carrier magazine embodying my improvements;

Fig. 2 is a sectional side elevation of the 40 magazine, looking in the opposite direction from Fig. 1; and

Fig. 3 is a sectional elevation, taken along the line 3—3 in Fig. 2.

Referring to the drawings, I have shown 45 a weft carrier magazine having an end frame 10 supported by a bracket 11 secured to the loom frame 12. The frame 10 is provided with vertical guide ways or compartments 13 in which the butts of the weft carriers are guided. A similar end frame (not shown) is provided for supporting the tips of the weft carriers, the frames being fixed in spaced relation by a plurality of cross rods or tie bars 14 (Fig. 2). The

lowermost weft carrier B in each guide way 55 13 normally rests against the edge of a cradle 15 at the end of the guide way, as indicated at the right in Fig. 2.

Each guide way 13 is preferably provided with a fixed wall or rib 16 at one side thereof and may have a partial fixed wall 17 on the opposite side at the extreme lower end of the guide way. Throughout the greater portion of the length of the guide way, however, the second side wall is formed by a 60 strip or plate 18 of spring steel or other resilient material, the lower end of which is preferably secured in a recess in the upper end of the side wall portion 17, the parts being secured together by a screw 19 65 or in any other convenient manner.

The plate or spring 18 is preferably offset inwardly above its attachment to the part 17 and at its upper end is curved outwardly to engage a guide or rest 20. An offset cam 70 plate 21 (Fig. 3) is also secured to the outside of the spring 18 intermediate its ends for a purpose to be described.

Under normal conditions, the spring 18 75 presses inward against the butts of the bobbins B, forcing the butts against the fixed side wall 16 and gripping them with sufficient force to prevent relative angular movement thereof.

Slide bars 22 are mounted on the outer 80 face of the magazine end frame 10, said bars being normally in the lowered position shown at the left in Fig. 1, but being raised to the position shown at the right in Fig. 1 upon indication of transfer. The mechanism 90 by which this movement is effected and controlled forms no part of my present invention and for a more complete description thereof, reference is made to the prior patents to E. H. Ryon, No. 1,022,108 and No. 1,030,748.

As a slide bar 22 is raised, the corresponding cradle 15 is rocked from the position shown at the right in Fig. 2 to the position shown at the left thereof. At the same time the upper end of the slide 22 engages the corresponding cam plate 21 and withdraws the plate or spring 18 from engagement with the weft carrier butts as indicated at the left in Fig. 2, the lowermost weft carrier being thereafter supported in the cradle 15 in a position to be advanced to transfer position when the cradle is returned to its nor- 100 105

mal position by subsequent downward movement of the slide bar 22. Such downward movement of the slide bar also releases the plate 18 to engage the weft carrier butts and prevent angular movement thereof.

A particular advantage is attained by engaging the weft carriers at the sides of the butts, as these butts are the portions by which the weft carriers are supported in the 10 shuttles and are therefore carefully gauged so that they are of substantially uniform diameter.

Having thus described my invention it will be seen that my improvements are of 15 exceedingly simple construction and add no moving parts to the magazine, with the exception of the slight inward bending of the springs 18. Accordingly there is nothing 20 to become displaced or to require adjustment and the device will operate as designed for an indefinite period.

Having thus described my invention, I do not wish to be limited to the details herein disclosed otherwise than as set forth in the 25 claims, but what I claim is:—

1. In a weft carrier magazine, an end frame having a plurality of substantially vertical guide ways for the butts of the weft carriers, said guide ways being effective to 30 grip the sides of said weft carrier butts at the opposite ends of the diameter thereof during normal operation of the loom, and means to release the grip upon the weft carrier butts upon indication of transfer.

2. In a weft carrier magazine, an end frame having a plurality of substantially vertical guide ways for the butts of the weft carriers, each guide way having a fixed 40 portion engaging the weft carrier butts at one side and having a movable portion yieldingly engaging said butts on the opposite

side, and means to withdraw said movable portion and release the weft carriers upon indication of transfer.

3. In a weft carrier magazine, an end 45 frame having a plurality of substantially vertical guide ways for the butts of the weft carriers, each guide way having a fixed side wall engaging the weft carrier butts upon one side and having a longitudinally 50 disposed flat spring plate yieldingly engaging the weft carrier butts upon the opposite side, and weft controlled means engaging one of said springs upon indication of transfer to bend it outwardly and release the corresponding weft carriers.

4. In a weft carrier magazine, an end 55 frame having a plurality of substantially vertical guide ways for the butts of the weft carriers, one side wall of each guide way 60 being fixed and the other side wall yieldingly engaging the weft carrier butts, a cam plate on each movable wall, and an actuating member for each guide way movable to engage a cam plate upon indication of transfer and thereby withdraw said movable wall to release the corresponding weft carriers.

5. In a weft carrier magazine, an end 70 frame having a plurality of substantially vertical guide ways for the butts of the weft carriers, one side wall of each guide way being fixed and the other side wall comprising a flat spring plate fixed at its lower end and having its upper portion yieldingly 75 movable inwardly to engage the weft carrier butts, and means operative upon indication of transfer and engaging said spring plate to withdraw said plate and release the weft carriers.

In testimony whereof I have hereunto affixed my signature,

OSCAR W. RICHARDSON.
